UNITED STATES PATENT OFFICE.

GEORGE W. MILLER, OF WOONSOCKET, RHODE ISLAND.

MACHINE FOR PRESSING FABRICS.

SPECIFICATION forming part of Letters Patent No. 352,253, dated November 9, 1886.

Application filed January 6, 1885. Serial No. 152,175. (No model.)

To all whom it may concern:

Be it known that I, GEORGE W. MILLER, a citizen of the United States, and a resident of Woonsocket, Providence county, Rhode Island, have invented certain new and useful Improvements in Machines for Pressing Fabrics, of which the following is a specification.

My invention relates to that class of machines in which fabrics are pressed between revolving cylinders and beds arranged adjacent to said cylinders; and my invention consists in means, fully set forth hereinafter, for regulating the pressure upon the fabric, for removing it therefrom, for directing one or more fabrics to the cylinder, and for pressing continuously without friction or ironing.

In the drawings, Figure 1 is a perspective view of a pressing-machine illustrating my improvements. Fig. 2 is a sectional elevation. Fig. 3 is a detached view illustrating the arrangement of the cylinder, beds, and pressure-regulating appliances. Fig. 4 is a view illustrating the arrangement of the carrying-bands.

25 The side frames, A, of the machine are suitably connected and constructed to support the operating parts hereinafter described.

Between the frames is secured the lower presser-bed, B, having a concave upper surface adapted to the cylinder C, the shaft d of which cylinder turns in bearings d', adapted to vertical guides in the frame.

To each side frame is connected by a link, f, a lever, D, in the outer end of which lever turns a shaft, g, that passes through slots x in vertical rods U, and which is provided with a handle, g', and carries eccentrics P, bearing upon friction-rolls b b on the rods U. The lower end of each rod U is connected to a lever, R, pivoted at one end, carrying a weight, W, and extending at the opposite end over a rod or bearing, y, as in the device patented to me September 18, 1883, No. 285,052. Each lever D is provided with two side ears or wings, 45 5, extending below the lower edge, and with vertical slots, and each bearing d' is provided with an ear, 6, at the top, which ear fits between the ears 5, and carries a pin, e, which enters the slots in the ears 5, forming a loose 50 connection between the levers and bearings, which permits a limited play of the levers independently of the bearings.

The upper pressure-bed, B', has a curved under face corresponding to the cylinder, and a projection at each end extends over the lever below and is secured to each by bolts a' a'. Center bearing screw-bolts, a, extend through the projections or ends of the bed B', and may be adjusted to bear on the tops of the ears 6, so as to elevate the levers D until 60 the pins e are at the lower ends of the slots in the ears 5, to then prevent any movement of the levers independently of the bearings d', and the upper pressure-bed is held away from the cylinder while the lower bed only 65 is used, and no goods are pressed by the upper bed. On the end of the shaft d is a toothed wheel, W', which gears with a pinion, X', upon a shaft, X.

By the arrangement of parts above described 70 I am enabled to relieve the fabric first of the pressure of the weight W, then to separate the upper bed from the cylinder, and then lift the cylinder, with the upper bed, to separate the cylinder from the lower bed, and also to lift 75 the wheel W' from its connection with the driving-pinion X'. This is effected by a single movement of the shaft g. Thus the parts being in the position shown in Fig. 3, and the shaft g being turned in the direction of its arrow, the rod U will first descend until the levers R take their bearings on the rod y, when the weight W will no longer act to depress the levers D, and the cylinder will be relieved of the pressure of this weight. The continued 80 movement of the shaft g will then lift the levers D and carry the upper bed away from the cylinder, so that there can be no pressure on the fabric between them. When the pins e are in the lower ends of the slots 5 in the levers, the bearings d' and the cylinder will be 85 lifted from the lower bed, the fabric being thus relieved from pressure upon both sides of the cylinder. As the rotation of the shaft g elevates first the levers D and then bearings d' 90 and shaft d, the wheel W' is raised with the bearings from its connection with the pinion X', when the rotation of the cylinder will be arrested.

Rolls F G' G² H' H² are supported to turn 100 in suitable bearings in the frame of the machine, and a carrying band or apron, F², passes around the roll F and around the cylinder, another band, H, passes around the upper bed

- and around rolls $H' H^2$, and between the lower bed and the cylinder passes a band, G , which extends around the rolls G' and G^2 . This permits the fabric to be passed between the bands $H F^2$ upon the upper side of the cylinder, and then between the bands $F^2 G$ upon the lower side of the cylinder, so as to receive two pressures, or it permits two fabrics to be pressed at once, one, Y , Fig. 4, being carried from a bundle, p' , over tension-bars downward and between the band F^2 , Fig. 4, and the band H , and the other, Y^2 , being carried from the bundle p' between the band F^2 and the band G , upon the opposite side of the cylinder, but in a contrary direction. In cases where the face of the fabric is to be planished it may be carried in direct contact with the polished face of the bed and cylinder instead of between two of the bands.
- At each side of the cylinder C , but in different planes, is located a stretcher-cylinder, I , and adjacent to each stretcher-cylinder is a steamer, V , the said cylinders and steamers being of any ordinary or well-known construction.
- Upon shafts turning in bearings upon the front end of the machine are carried suitable brushes, $J J'$, the brush-shafts being driven by a belt, J^4 , which passes around guide-pulleys $J^5 J^6$, and around a pulley upon the driving-shaft X^2 , so that the brushes are rotated in opposite directions. A tension-roll, K , is supported at the upper front portion of the frame above a guide bar or roll, K' , and a guide bar or roll, K^2 , is arranged at the rear of the brush J . Some fabrics require brushing on one side only, and some upon both, and the amount of brushing required varies with the character of the goods.
- In order to properly conduct and operate upon the fabric, I employ, in connection with the brushing and guiding rolls, suitable regulating or guide bars, $L L'$, hung between arms m upon shafts $N N'$, supported in bearings in the frame, and each shaft carrying at one end a slotted plate, I^2 , through the slot of which a bolt, I' , passes into the frame to serve as a means of securing the shaft in place after its adjustment, a handle, Q^3 , serving as a ready means of rocking the shaft. The fabric is carried from the bundle or file P' over roller K' , past the under side of brush J , between the lower guide-bar, L , and the brush J' , directly upward past brush J' , to the roller K^2 , and over the upper brush, J , and then under the upper guide-bar, L' , and over and around the tension-roll K .
- The extent to which the fabric is submitted to the action of the brushes $J J'$ will depend upon the position of the guide-bars $L L'$ in respect to the brushes, the fabric being folded to a greater extent around the periphery of the brushes in proportion as the guide-bars are brought nearer to the latter. In like manner the position of the adjustable guide bar L^3 in respect to each stretching-roll I deter-

mines the extent to which the fabric is presented to the said roll, and the adjustment of the fabric thereby varies the extent of the action of the roll thereon.

It will be seen that by the means above described the path of the fabric can be easily controlled, so as to bring it in contact upon both sides with the brushes to a greater or less extent, and so as to vary the amount of surface subjected to the action of the stretching-rolls.

It will of course be understood that the various operating parts are connected by suitable gears or belts, so as to be operated in unison from the single driving-shaft.

The guide-bars $L L' L^3$, instead of being carried by arms upon a rock-shaft, may be adjustable in slots in the side frames of the machine, so as to permit them to be moved in respect to the brushes or rollers; or any other known equivalent means of securing said adjustment may be employed, and any suitable known and equivalent clamping appliances may be used for securing the said bars after they are adjusted.

The levers D may have link or other known equivalent connections with the upper bed, B' , which will permit a limited movement of the levers in respect to the said bed.

In an application filed by me May 19, 1884, and numbered 131,970, I have shown and claimed a press with a stationary bed and revolving cylinder, and bands passing between the same and carried and guided by rollers; hence I do not claim such constructions in this application.

Without limiting myself to the precise construction and arrangement of parts shown and described, I claim—

1. The combination, with the cylinder and upper and lower beds and cylinder-bearings, of levers D , having loose connections with the bearings of the cylinder, and arranged to lift the upper bed when elevated, and the weighted levers R , rods U , movable connections between the rods and levers D , and stops y , all substantially as set forth.

2. The combination of the cylinder, its shaft, lower fixed bed, upper movable bed, levers D , connected to the upper bed and loosely connected with the cylinder-bearings, wheel W' upon the shaft of the cylinder, pinion X' , shaft X , weighted levers R , rods U , adjustable connections between the rods and levers D , and rods y , substantially as set forth.

3. The combination of the cylinder-bearings d' , lower fixed bed, B , upper bed, B' , levers D , connected to the upper bed and having slotted ears 5 , devices, substantially as described, for moving the levers, and ears on the bearings 5 , having pins extending into the slots of the ears 5 , substantially as set forth.

4. The combination of the cylinder C , cylinder-bearings d' , beds $B B'$, levers D , having connections with the bearings permitting of limited vertical play independently thereof, weighted levers R , rods U , and adjustable con-

nections, substantially as described, between the rods U and levers D, substantially as set forth.

5. The combination, with the cylinder and upper and lower beds, B B', and continuous belts G and H, and belt-supporting rolls, of a roll, F, and belt F², passing round said roll and round the cylinder, substantially as set forth.

6. The combination of the cylinder-bearings

d', levers D, loosely connected to the bearings, and screw-bolts, substantially as and for the purpose set forth.

In testimony whereof I have signed my name to this specification in the presence of two subscribing witnesses.

GEORGE W. MILLER.
